UNITED STATES PATENT OFFICE

2,504,217

REFRIGERATED PHOTOGRAPHIC
FINISHING EQUIPMENT

Frank A. Nelson, Jesse W. Berry, Walter F. Robinson, and Louis B. Orendorff, Kansas City, Mo.

Application February 24, 1948, Serial No. 10,418

3 Claims. (Cl. 62—11)

1

This invention relates broadly to the field of refrigeration and more specifically to equipment particularly adaptable for use in finishing photographs.

The primary object being to provide a refrigerated cabinet adaptable not only to store the chemicals and other apparatus used by the photographer but to maintain chemicals within the developing pans at a desired predetermined temperature.

The most important object of this invention is a provision for photograph finishing cabinets having a number of compartments formed therein; one of which is disposed along the top of the cabinet for containing a liquid to be cooled and adaptable to support a number of the photograph developing trays.

Another important object of this invention is to provide photograph finishing cabinet having a cooling apparatus common to various compartments thereof and disposed particularly in underlying relationship to an open top compartment and extending into compartment of the cabinet to simultaneously cool the developing trays within the open top compartment and to maintain the second cooling compartment at a predetermined temperature.

Other objects of this invention include the way in which the various compartments of the cabinet are separated by insulated walls, the way in which the refrigerating mechanism is segregated within the cabinet from the cooled compartments thereof, and the manner in which the open top tray and the underlying cooling coils are drained through a common conduit.

Other objects of this invention will be made clear during the course of the following specification, reference being had to the accompanying drawing; wherein,

Figure 1 is a perspective view of the refrigerated photograph finishing equipment made in accordance with the present invention; and

Fig. 2 is a substantially central vertical cross-sectional view taken on line II—II of Fig. 1.

The cabinet shown in the drawing and broadly designated by the numeral 10 constitutes an upright, hollow structure having a pair of opposed side walls 12 and 14, and end walls 16 and 18, supported by a plurality of feet or legs 20. The top of cabinet 10 is open and a horizontal partition 22 spaced from the uppermost end of the cabinet 10 sets forth a relatively shallow compartment 24. A vertical partition 26 divides the remainder of the cabinet 10 into a pair of compartments 28 and 30. A portion of the bottom

2

32 of the cabinet 10, together with end wall 18 and vertical partition 26 is of double-wall construction, as clearly shown in Fig. 2 of the drawings, and has suitable insulation 34 disposed between such double walls.

Secured to the horizontal partition 22 which constitutes the bottom of compartment 24 in underlying relationship thereto is a relatively flat, shallow pan 36. This pan 36 is partly disposed within the compartment 30 of cabinet 10 and extends along the uppermost edge of the framework partition 26 into a chamber 38 overlying the compartment 28. A plurality of refrigerating coils 40 disposed within this pan 36 and in direct underlying relationship to the compartment 24 has connection with a conventional refrigerating compressor 42 through a pair of connecting conduits 44 and 46.

This compressor 42, together with a prime mover, preferably in the form of an electric motor 48, is mounted within the compartment 28 and directly upon a bottom wall 50 thereof. This compartment 28 is bounded on one side by the uninsulated wall 16 and on the opposite side by a double-wall vertical partition 26.

One end of the compartment 28 forming a part of the side wall 14 of cabinet 10 has an access opening 52 formed therein, while a similar access opening in opposed relationship thereto and formed in the side wall 12 of cabinet 10 is covered by a removable plate 54, attached to wall 12 by means of a number of screws or the like 56.

It is notable as illustrated in Fig. 2 that the insulated end wall 18 of cabinet 10 extends upwardly beyond the horizontal partition 22.

By the same token, a portion of the end wall 16 above compartment 28 is of double-wall construction for receiving insulation 34 as at 58.

By the same token, that part of the side walls 12 and 14 defining the compartment 30 is of double-wall construction and contains insulation 34 and also extends upwardly beyond the partition 22 to set forth the compartment 24.

A pair of spaced apart walls having insulation 34 therebetween and disposed horizontally within the cabinet 10 between the compartment 26 thereof and the chamber 38. This horizontal divided partition is designated by the numeral 60.

The compartment 24 is adaptable to contain a filling of liquid 62 wherein is disposed a plurality of film developing pan 64. An L-shaped conduit 66 having connection with a suitable drain (not shown) joins with the partition 22 for draining the liquid 62 of compartment 24 as desired. A suitable plug 68 within the conduit 66 holds the

liquid 62 within the compartment 24 as shown in Fig. 2. This L-shaped conduit 66 extends downwardly from the partition 22 through the double partition 60 and thence outwardly through an opening formed in the end wall 16 of cabinet 10.

A second L-shaped conduit 70 interconnects the pan 38 and the conduit 66 to receive any condensate from the refrigerating coils 40. Access to the compartment 30 is through a hingedly mounted closure 72 of conventional character and any number of shelves such as at 74 may be mounted within the compartment 30 for receiving the various photographic chemicals used.

The liquid 62 within the compartment 24 is maintained at a desired temperature through the medium of a thermal bulb 76 disposed within the liquid 62 and having connection with a switch 78 mounted within compartment 28 by means of a conduit 80. This switch 78 is joined to the motor 48 by wires 82 and to a suitable source of electrical energy (not shown) by means of a cord 84.

It is readily seen from the foregoing that the cabinet 10 serves the dual purpose providing a cabinet 30 that is maintained at a desired cooled temperature for receiving the chemical and other materials used by the photographer, and at the same time providing means for maintaining the chemical within developing pans 64 at a predetermined temperature.

The pans 64 are disposed conveniently at the top of cabinet 10 within the cooled liquid 62 and may be easily removed for draining of chemical therein or for cleaning as desired.

By the same token, the compartment 24 may be easily cleaned by removal of the plug 68 to drain liquid 62 therefrom. The cooling coils 40 are utilized not only to cool the liquid 62 but to maintain compartment 30 in a refrigerated condition and all condensate forming thereon will ordinarily drain down conduit 70.

Both the compartment 24 and the compartment 30 are well insulated from the compartment 28 and the refrigerating mechanism including motor 48 and compressor 42 is conveniently housed and segregated from compartments 24 and 30.

While only one modification of the present invention has been illustrated and described, it is to be understood that many changes and modifications may be made without departing from the spirit of this invention as defined by the scope of the appended claims.

Having thus described the invention, what is claimed as new and desired to be secured by Letters Patent is:

1. A photograph finishing cabinet comprising an open top body; a horizontal partition mounted in the body adjacent said open top thereof presenting a shallow compartment thereabove adapted to contain a liquid filling, said partition being formed from a heat-conducting material; cooling structure underlying said partition; a housing formed from heat-con-

ducting material and depending from the partition, said housing being formed to cooperate with the partition in enclosing the cooling structure; a vertical partition depending from the housing and setting off a pair of separate chambers in the body below the horizontal partition; and apparatus in one of said chambers operably connected with said structure for cooling the same.

2. A photograph finishing cabinet comprising an open top body; a horizontal partition mounted in the body adjacent said open top thereof presenting a shallow compartment thereabove adapted to contain a liquid filling, said partition being formed from a heat-conducting material; cooling structure underlying said partition; a housing formed from heat-conducting material and depending from the partition, said housing being formed to cooperate with the partition in enclosing the cooling structure; a vertical partition depending from the housing and setting off a pair of separate chambers in the body below the horizontal partition; and apparatus in one of said chambers operably connected with said structure for cooling the same, all walls of the other chamber including said vertical partition and exclusive of said housing and said horizontal partition being insulated.

3. A photograph finishing cabinet comprising an open top body; a horizontal partition mounted in the body adjacent said open top thereof presenting a shallow compartment thereabove adapted to contain a liquid filling, said partition being formed from a heat-conducting material; cooling structure underlying said partition; a housing formed from heat-conducting material and depending from the partition, said housing being formed to cooperate with the partition in enclosing the cooling structure; a vertical partition depending from the housing and setting off a pair of separate chambers in the body below the horizontal partition; and apparatus in one of said chambers operably connected with said structure for cooling the same, the walls of the other chamber including said vertical partition and exclusive of said housing and said horizontal partition being insulated, said one chamber having an insulated top wall separating the same from the housing and from the horizontal partition.
